FIG. 2.

FIG. 3.

UNITED STATES PATENT OFFICE

2,387,600

COMBUSTION APPARATUS

Donald J. Mosshart, Ardmore, Pa., assignor to
Westinghouse Electric Corporation, East Pitts-
burgh, Pa., a corporation of Pennsylvania

Application March 21, 1942, Serial No. 435,647

5 Claims.

(Cl. 110—38)

This invention relates to furnaces, more particularly to those of the stoker-fired type, and has for an object to provide novel and improved apparatus of this character.

A further object of the invention is to provide a spreader-fed stoker wherein fuel is deposited on a central portion of the fuel-supporting grate surface, where it is partially coked and ignited and then is fed laterally in opposite directions over side portions of the grate surface where it is consumed.

Another object of the invention is to provide a progressive-feed grate structure wherein a plurality of bars of inverted-V configuration extend transversely of the stoker in side by side relation, a number of the bars being stationary, and the remainder being reciprocatory and interspersed among the stationary bars.

Yet another object of the invention is the provision, in a spreader-fed progressive feed stoker, or pressure responsive means for maintaining a predetermined ratio between rate of feed of fuel to the grate and rate of flow of air to the fuel-fed portion of the grate.

These and other objects are effected by the invention as will be apparent from the following description and claims taken in connection with the accompanying drawings, forming a part of this application, in which:

Fig. 1 is a longitudinal sectional view taken along the line I—I of Fig. 3, looking in the direction of the arrows;

Fig. 2 is a horizontal sectional view, taken along the line II—II of Fig. 1, looking in the direction of the arrows;

Fig. 3 is a transverse sectional view taken along the line III—III of Fig. 2, looking in the direction of the arrows;

Fig. 4 is a view in perspective of one of the moving grate bars; and,

Fig. 5 is a side elevational view of one of the stationary grate bars.

Referring now to the drawings more in detail, there is shown, at 10, a furnace comprising front and rear walls 11 and 12, respectively, and side walls 13. Positioned within the lower portion of the furnace 10 is a stoker 14, comprised by a row of alternate moving and stationary grate bars 15 and 16, respectively.

A plurality of wall members 20, together with structural steel members 21 and 22, carried thereby, extend from front to rear of the furnace and constitute supports for the row of grate bars.

The moving bars 15 are provided at their lower

sides with supporting surfaces adapted to slidably engage the upper surfaces of the supporting members 21 and 22, the stationary bars 16 also having flat supporting surfaces at their under sides for similar engagement with the supporting members.

In order to impart transverse reciprocatory motion to the moving bars 15, the latter are each provided with a depending yoke member 24 adapted to receive a pin 25 projecting upwardly from a drive shaft 26, the latter extending longitudinally of the row of grate bars from front to rear of the furnace, the forward end of the shaft 26 projecting forwardly through the front wall 11 of the furnace and being equipped with suitable linkage 27 through which oscillatory motion may be imparted thereto by suitable means, not illustrated.

In order to prevent any transverse reciprocatory motion of the stationary bars 16, the latter are provided with a plurality of depending lugs 29 and 30 adapted to engage laterally against the sides of the top flanges of the supporting members 21 and 22.

A desirable feature of the grate bar construction just described is that both types of bars, that is, reciprocatory and stationary, may be removed and replaced by a simple vertical movement and without the disengagement of any fastening means, such as bolts, clamps, etc.

In the construction herein illustrated, both moving and stationary bars are shown as being of composite construction, each bar comprising a pair of identical bars joined together rigidly by suitable means, such as the bolts 32. In order to provide for the desired flow of air between the adjacent grate bars, the side surfaces of the bars are provided with a plurality of ribs 33, disposed approximately horizontal, although the angular disposition of these ribs may be varied to suit the requirements of a particular installation or set of operating conditions.

It will be apparent from consideration of Fig. 3 that the supporting members 20, 21 and 22 serve the added function of dividing the space beneath the row of grate bars into a central plenum chamber 35 and a pair of side plenum chambers 36. A plurality of ducts 38, 39 and 40 serve to conduct air under pressure to the plenum chambers from a suitable source, for example, the blower 41.

In order to control the supply of air to the central plenum chamber 35, there is provided in the duct 38 a metering orifice 42 followed by a damper 43. Pressure-responsive apparatus, at 44, provides for variation in the flow of air to the chamber 35

in direct proportion to variations in the quantity of fuel fed to the grate, as will be more fully explained hereinafter.

Coal from the hopper body 45 is fed, by means of a plurality of rams 46, through the opening 47 in the furnace front wall 11, where the spreader 48 sprinkles the coal over a central portion of the great surface which is in communication with the plenum chamber 35, this central portion extending from front to rear of the furnace.

A variable speed motor 50, driving through belts 51 and 52, operates both the ram 46 and the spreader 48.

In order that the supply of air to the central plenum chamber 35 may be varied in direct proportion to changes in rate of feed of fuel to that portion of the grate surface overlying the plenum chamber 35, the motor 50 is directly connected to a tachometer blower 52a which supplies air under pressure to a bellows 53, the latter being connected through the compression spring 54 to one end of the lever 55, pivotally mounted intermediate its ends on a fixed support, at 56. The compression spring 54, whose tension may be adjusted by the screw 57, urges the right-hand end of the lever 55 upwardly with respect to the bellows 53. The left-hand end of the lever 55 is connected through the rod 58 to a pair of spaced bellows 60 and 61, the former being in communication with the upstream side of the metering orifice 42 and the latter being in communication with the downstream side thereof. The lever 55 is also connected through the stem 62 with the valve 63 controlling flow of pressure medium through the conduit 64, the latter being in communication with the expandible chamber 65, enclosed in part by the movable piston or abutment 67, which is connected by the rod 68 with the bell crank 69, fixedly secured to the damper 43 in the passage 38. A compression spring 71 exerts force in the piston or abutment in opposition to the force of fluid pressure acting thereon.

In operation, it will be apparent that any increase in the rate of feed of fuel to the grate surface will result in increased speed of the tachometer blower 52a and increased pressure within the bellows 53. This in turn will produce upward movement of the right-hand end of the lever 55 and opening of the valve 63. As a result, the pressure within the chamber 65 will be increased, causing downward movement of the piston 67 and rod 68 carried thereby, thereby further opening the damper 43, resulting in increased flow of air to the central plenum chamber 35. As the chamber opens, the differential pressure across the metering orifice 42 decreases, resulting in upward force and movement applied to the left-hand end of the lever 55. The lever will move until equilibrium of forces acting thereon is restored with the valve 63 adjusted for the increased fuel feed rate. If the rate of fuel feed is decreased, the contrary operation takes place. By adjusting the spring 54, the relation of fuel feed rate to air flow rate to the central duct 38 and plenum chamber 35 may be varied.

Preferably the spreader 48 is so dimensioned and positioned that the stream of fuel deposited thereby upon the fuel supporting surface of the grates will lie along the central portion to which air is supplied from the central plenum chamber 35 with the result that there is produced on this central portion a loose, partially coked and ignited fuel bed adapted to be fed laterally of the stoker as the result of reciprocation of the movable grate bars 15, the fuel being consumed as it passes over

the side portions of the fuel supporting grate surface overlying the side plenum chambers 36. Ash and unconsumed refuse leaving the lower ends of the grate bars may be received upon ash dump plates 70 and periodically discharged into the ash pits 71 provided at each side of the furnace.

While in the embodiment herein illustrated, the furnace has been shown as containing only one stoker, it will be apparent that the invention 10 is not limited to this arrangement but may include the provision of two or more stokers disposed in side by side relation and extending from front to rear of the furnace, together with a corresponding number of fuel feeding and spreading devices associated therewith.

While the invention has been shown in but one form, it will be obvious to those skilled in the art that it is not so limited, but is susceptible of various changes and modifications without departing 20 from the spirit thereof, and it is desired, therefore, that only such limitations shall be placed thereupon as are specifically set forth in the appended claims.

What is claimed is:

25 1. A furnace having front, rear and side walls; a stoker disposed in the lower portion of said furnace and comprising a row of transversely-disposed grate bars, which row extends from front to rear of the furnace and comprises a plurality of reciprocatory bars interspersed among a plurality of stationary bars and provides a fuel-supporting surface of inverted-V shape in transverse section having a central portion adjacent the apex of the inverted-V flanked by two side portions at the legs 30 of the inverted-V; means for feeding coal through the furnace front wall a material distance above the fuel-supporting surface and spreading it over the central portion thereof from front to rear of the furnace; and means for imparting transverse reciprocatory motion to the reciprocatory bars to feed the coal from said central portion laterally in opposite directions over the side portions.

40 2. A furnace having front, rear and side walls; a stoker disposed in the lower portion of said furnace and comprising a row of transversely-disposed grate bars, which row extends from front to rear of the furnace and comprises a number of reciprocatory bars interspersed among a number of stationary bars, said row of bars providing a fuel-supporting surface of inverted-V shape in transverse section having a central portion adjacent the apex of the inverted-V and side portions at the legs of the inverted-V, means for feeding coal through the furnace front wall and spreading it over said central portion of the fuel-supporting surface from front to rear of the furnace for partial coking and ignition thereon, a first means carried by each reciprocatory bar, and second means extending longitudinally of the row of grate bars and engaging said first means, said first and second means being adapted to impart transverse reciprocatory motion to the reciprocatory bars to feed the partially coked and ignited coal from the central portion laterally over the side portions for consumption at said side portions.

65 3. Structure as specified in claim 2, wherein the row of transversely-disposed grate bars comprises alternate reciprocatory and stationary bars.

4. Apparatus of the character described comprising a furnace; grate structure within the furnace; fuel-feeding mechanism of the sprinkler or spreader type for spraying fuel freely over a central portion of the grate, which portion extends from front to rear of the furnace and is spaced

from the side walls thereof, whereby a substantial portion of combustion takes place while the fuel is in suspension; and means for imparting movement to the grate structure to feed the fuel transversely of the furnace along the grate from the central portion to the sides of the furnace.

5. Apparatus of the character described comprising a furnace; grate structure within the furnace providing a fuel-supporting surface of inverted-V shape in transverse section having a 10 central portion adjacent the apex of the inverted-

V flanked by two side portions of the legs of the inverted-V; fuel-feeding mechanism of the sprinkler or spreader type for spraying fuel freely over said central portion of the grate, which portion extends from front to rear of the furnace, whereby a substantial portion of combustion takes place while the fuel is in suspension; and means for imparting movement to the grate structure for feeding the fuel from said central portion laterally in opposite directions over said side portions.

DONALD J. MOSSHART.

CERTIFICATE OF CORRECTION.

Patent No. 2,387,600.

October 23, 1945.

DONALD J. MOSSHART.

It is hereby certified that error appears in the printed specification of the above numbered patent requiring correction as follows: Page 1, first column, line 21, for "or pressure" read --of pressure--; page 2, first column, line 7, for "great" read --grate--; and that the said Letters Patent should be read with this correction therein that the same may conform to the record of the case in the Patent Office.

Signed and sealed this 22nd day of January, A. D. 1946.

Leslie Frazer

First Assistant Commissioner of Patents.
